JUVENILE BOOK

Spencer Leubrie, New York, N. Y.

Application March 22, 1935, Serial No. 12,373

6 Claims. (Cl. 35—26)

The present invention relates to improvements in tracing books of amusement and educational value more particularly designed for the use of juveniles.

5 While the following disclosure deals especially with books as above described, books incorporating some or all of the features hereinafter disclosed may be profitably employed in other fields. In the mercantile field, they may be used as 10 order books and sales books; in schools or technical professions, as note books, etc.

The invention contemplates the provision of a book incorporating at least two major sections, one section comprising bound sheets embellished 15 with drawings, paintings, diagrams, etc.; and the other comprising bound sheets of tracing paper or the like arranged so that the top sheet of the latter section may be superimposed on either surface of any of the sheets of the first-mentioned section whereby the user may trace 20 upon said top sheet of tracing paper, the illustration on the sheet which it is superimposed on.

More specifically, the invention contemplates the provision of a book in which one section of sheets is bound along one edge and another section of transparent sheets is bound along another edge so that the topmost sheet of the latter section may be superimposed on either surface of any of the sheets of the first-mentioned section, said sections being each bound to a common 30 member.

The invention further contemplates the provision of a book structure as above described in which is incorporated one or more sheets of carbon paper or the like, hinged along a line other than the mentioned bindings whereby said carbon paper may be associated with the other sheets when manifold copies are desired.

Other contemplated features of the invention 40 such as the provision of binding means particularly adapted to the purposes of the invention; the provision of means to replace a used up section in a quick and facile manner, etc., will become more readily apparent from the following 45 specification and the accompanying drawing.

In the drawing:

Fig. 1 is a top view of a book constructed in accordance with this invention.

Fig. 2 is a view in perspective of the book arranged for use.

Fig. 3 is a similar view of said book showing another condition of use.

Fig. 4 is an enlarged fragmentary sectional detail view showing an alternate form of book structure.

Fig. 5 is a perspective view of a sheaf or stack of tracing paper as disclosed in Fig. 4.

Fig. 6 is an open plan view, partly broken, of a book incorporating carbon paper.

Describing the drawing in greater detail, and with particular reference to Figs. 1, 2 and 3, the book comprises the two major sections 10 and 11.

The section 10 preferably comprises a plurality of sheets 12, bound together as by means of the spiral binding or the like 13 so that the section may be opened between any of the sheets to lay flat without bulging at the binding.

The section 10 is preferably bound together with a member 14 of somewhat greater thickness to afford rigidity to the book.

The section 11 is preferably comprised of a sheaf or stack of tracing sheets 15 bound together and to the backing member 14 by a spiral binding 16. In the present instance, this binding is preferably disposed at right angles to the binding 13 although it may be disposed parallel thereto if desired.

Some or all of the sheets 12 of the section 10 may bear on one or both surface illustrations or the like as indicated at 17. These may be in outline or colored; or may be diagrams or maps such as may be utilized in technical fields or in the study of geography, anatomy, etc.

From the foregoing, it is apparent that if any illustration, diagram or map is to be traced, the section 10 is opened to expose said illustration and the topmost sheet of the sheaf of tracing paper is superimposed over said exposed illustration, either as shown in Fig. 2 when the illustration is on the right hand side of the opened section or as shown in Fig. 3 when the illustration is on the left hand side.

After being so used, the sheet of tracing paper may be torn out of its binding 16 or may be thrown around to the back of the member 14 to expose for use the next sheet 15 of the sheaf 11.

The improvement illustrated in Figs. 4 and 5 comprises the book structure above described with the added feature which comprises means 45 to quickly replace a used up sheaf of tracing paper. This sheaf 15 is bound together at 16 with a short relatively stiff auxiliary sheet 18 designed to be removably attached at 19 to the backing sheet 14 of the book as by the means shown at 20. In this form of book structure, it is apparent that the section 10 of the book may remain intact at all times and that the sheaf 15 which has been used may, without mutilation, be stored away for future use or reference.

In certain instances, it may be desired to obtain more than one copy or tracing of the subject on any of the sheets 12. In that event, a structure such as shown in Fig. 6 may be employed. This structure is as above described with the addition of one or more sheets of carbon paper or the like 21 secured to a portion of the book such as 14 in a manner whereby it may be disposed over the face of any one of the sheets 12 or 15. In this manner, also, copies of illustrations may be made not only on the thin tracing sheets 15 but also on the heavier sheets 12, some of which may be blank for the purpose. This book structure particularly lends itself to use 15 as an order, sales or copy book as previously set forth.

While the invention has been shown and described in several of its preferred embodiments, immaterial structural changes may be made by 20 those skilled in the art without departing from the spirit and scope of the invention. The prior art, therefore, rather than this specific disclosure should determine the scope of the following claims.

25 I claim:

1. A book of the character described comprising a backing member; at least two sheafs of sheets, one of said sheafs consisting of transparent sheets only and binding means uniting 30 each sheaf to a different edge of said backing member for rotation through a complete angle of 360° whereby any selected transparent sheet of one sheaf may be superimposed on any selected surface of any one of the sheets of the other 35 sheaf in a flat, unstressed and undisturbed state.

2. A book of the character described comprising a backing member, a sheaf of sheets each having an illustration on both of its faces, a spiral binding uniting said sheaf to one edge of 40 the backing member, a sheaf of transparent sheets and another spiral binding uniting said latter sheaf to an edge of said backing member at right angles to the first-mentioned binding edge whereby any selected transparent sheet may 45 be arranged in contact with either illustration on any selected sheet of the first-mentioned sheaf.

3. A book of the character described comprising a backing member, a sheaf of illustration-bearing sheets bound along one edge of the 50 backing member for rotation relatively thereto through an angle of 360° free of distortion and stress, an auxiliary separate backing member, a sheaf of transparent sheets bound along one edge of said auxiliary member for rotation relatively 55 thereto through an angle of 360°, and means to removably unite the adjacent edges of said backing members to each other and to the sheaf of transparent sheets whereby any transparent sheet may be superimposed in a flat and undisturbed state over either surface of any illustrated sheet.

4. In a book, a first series of sheets each having markings on both faces thereof, a backing sheet, spiral means for separably binding said

first series of sheets along corresponding edges thereof to a corresponding edge of the backing sheet whereby said first series of sheets are hinged to swing through an angle of 360° in one direction relatively to the backing sheet, a series of blank transparent sheets, and spiral means for separably binding corresponding edges of the blank transparent sheets to an adjacent edge of the backing sheet whereby the blank transparent sheets are hinged to swing through an angle of 360° in a different direction relatively to the backing sheet and any selected one of the blank transparent sheets may be superimposed upon either selected face of any selected one of the first series of sheets, said binding means securing said sheets to the backing member to form a unitary structure.

5. In a copying book, a plurality of illustrated sheets each bearing on each of the faces thereof an illustration to be copied to provide twice as 20 many illustrations as there are illustrated sheets, a plurality of blank transparent copy sheets, each of said copy sheets being of less width than that of the illustrated sheets, a backing member for the copy sheets, said backing member being of 25 greater width than that of the copy sheets, said copy sheets and said backing member having registering spaced perforations in the adjacent end edges thereof, a spiral binding passing through said perforations, said backing member 30 having spaced perforations along a side edge thereof beyond the adjacent side edges of the copy sheets, and said illustrated sheets having a series of corresponding spaced perforations along the corresponding side edges thereof adjacent the perforated side edge of the backing member, and a second spiral binding passing through the side edge perforations of the illustrated sheets and of the backing member where- 35 by on rotation of said sheets and said backing member on said spiral bindings through the proper angle and in the proper direction any selected copy sheet may be superposed in a flat, unstressed, and undistorted state on a selected face of a selected one of the illustrated sheets. 45

6. A book of the character described comprising a backing member, a sheaf of transparent sheets, a spiral binding uniting said sheaf to an end edge of the backing member, a second sheaf of sheets each bearing illustrations on both faces 50 thereof, a second backing member separate from the first backing member, and a second spiral binding uniting a side edge of the second sheaf to a side edge of the second backing member and also joining the adjacent side edges of said 55 backing members together whereby said members may be relatively rotated through a complete angle of 360° while both of said members remain flat and undistorted and whereby any selected transparent sheet may be superposed in a flat state throughout on either face of any selected illustration bearing sheet. 60

SPENCER LEUBRIE.
